Term of patent 14 years

Int. Cl. D3—99

U.S. Cl. D87—1

FIG. 2

FIG. 1

Des. 221,821

PAGE 2

FIG. 3

FIG. 4

FIG. 5

FIG. 6

FIG. 1 is a perspective view of our new design for a carrying case;

FIG. 2 is a side view of the carrying case, the opposite side being a mirror image thereof;

FIG. 3 is a top view of the carrying case;

FIG. 4 is a rear view of the carrying case;

FIG. 5 is a front view of the carrying case; and

FIG. 6 is a bottom view of the carrying case.

We claim:

The ornamental design for a carrying case, substantially as shown and described.
